UNITED STATES PATENT OFFICE

SIMON L. WALDMAN, OF CHELSEA, MASSACHUSETTS, ASSIGNOR OF ONE-HALF TO JOHN WEBSTER, OF SAME PLACE.

LOCKING DEVICE FOR BUCKLES.

SPECIFICATION forming part of Letters Patent No. 352,103, dated November 2, 1886.

Application filed September 1, 1886. Serial No. 212,396. (No model.)

To all whom it may concern:

Be it known that I, SIMON L. WALDMAN, a citizen of the United States, residing at Chelsea, in the county of Suffolk and State of Massachusetts, have invented certain new and useful Improvements in Locking Devices for Buckles; and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

15 This invention relates to a locking device adapted to be removably attached to straps which are provided with buckles or other analogous fastenings. Thus when it is actively employed the buckle is clamped, and the strap is 20 prevented from being unloosened and disengaged from the article which it secures.

Briefly stated, this locking device is composed of two clasp-sections, through which the strap freely plays. One of said clasp-sections 25 contains locking mechanism, while the other is provided with a hasp. This latter is engaged by the locking mechanism. The length of the hasp is sufficient to extend across the buckle, fit closely down upon the latter, and 30 thereby prevents the tongue from being raised in order to release and disengage it from the strap.

The drawings represent in Figure 1 a side elevation, and in Fig. 2 a plan, of the underside 35 of a locking device embodying my invention. Fig. 3 is a perspective view of the hasp, and Fig. 4 a similar view of the locking clasp-section of the instrument.

In the drawings, A represents the device 40 as an entirety, composed of the two parts or clasp-sections B C, which are separable and adapted to be readily inserted upon or removed from a strap, (shown at D,) as occasion may require.

45 The clasp-section B is here represented as composed of sheet metal, suitably constructed, and in cross-section is rectangular in shape and rounded at one end, a, not only to obviate the sharp corners, which otherwise would be objectionable, but also to produce a more finished 50 appearance. The upper part of this clasp-section

tion B is constructed with a closed portion, b, which contains the locking mechanism of any suitable description, while the lower portion is open at two ends, and thus an orifice or passage-way, c, is produced, through which the loose end d of the strap D is to be passed, whereby the clasp-section is secured upon the strap. The other clasp-section, C, which is adapted to co-operate with the clasp-section B and form 60 the locking device A as an entirety, is similarly formed with its outer end rounded, and in cross-section is preferably rectangular and constructed of sheet metal folded upon itself or struck up in any desirable way to form a 65 hollow clasp-section, with an orifice, e, through which the strap is to be passed when the locking device is to be actively employed thereon. The upper portion of this clasp-section is extended and forms a hasp, f, provided with a 70 catch to engage the locking mechanism contained within the closed portion b, before mentioned. It will be seen that the length of this hasp is sufficient to permit it to engage the locking mechanism, and yet allow the buckle 75 or other fastening to be contained within the oppositely-disposed faces g h of the clasp-sections B C, respectively.

In Fig. 1 I have shown secured to one end, i, of the strap D an ordinary buckle, E, which 80 is prevented from being released by my locking device A. This latter instrument is applied, as shown in the drawings, in the following manner: The loose end d of the strap is inserted within the orifice e of the clasp-section 85 C, which is to be put on first, with the hasp f pointing toward that end of the strap to which the buckle is secured. The clasp-section B is then inserted upon the strap in a similar manner, with the key-hole end of said clasp-section 90 first. The order of introducing the clasp-sections B C may be reversed, as it is immaterial which is applied first upon the strap. The strap is now passed about the article to be fastened, the loose end d of the strap passed through 95 the buckle, and the strap firmly tightened, and thus held by the tongue j, which engages it. The end d is now passed through the orifice e of the clasp-section C in a reverse direction and drawn down in place. When this act is accomplished, the two clasp-sections are pushed 100 toward each other until their opposite ends, g

h, are contiguous to the ends of the buckle E. The hasp f now engages with and is secured by the locking mechanism in the clasp-section B, and the two parts are firmly united; hence it will be seen that so long as the lock remains intact and the hasp rests upon the front side of the buckle the tongue j cannot be changed from its present position and the strap cannot be released. Since the strap is to be passed through the clasp section twice, the depth of the orifice e is double that in the clasp-section B, as will be seen in the drawings; but in the event of applying the clasp-section B first, then the orifice in the latter should be made the greater in depth.

It is obvious that the size of the clasp-sections can easily be varied to suit the width and thickness of any strap. Furthermore, the simplicity of the device and its ready application to any strap without injury to the latter render it very efficient. In case the strap breaks, a new one may be easily substituted; or if it is to be used without the locking device the two clasp-sections are readily slipped off and locked together to prevent loss of either portion.

I claim—

1. In combination with a strap provided with a buckle, the clasp-sections removably disposed upon the strap, one at each end of the buckle, and locked by a connecting-link to prevent the buckle from being operated, substantially as stated.

2. A locking device for buckles, composed of a clasp-section, B, with its locking mechanism, and the clasp-section C, with its hasp f, adapted to unite the said clasp-sections and rest on the face of the buckle contained between the clasp-sections, as and for purposes herein stated.

3. The clasp-section B, provided with locking mechanism and the orifice e, in combination with the clasp-section C, its orifice e, and the hasp f, the said clasp-sections co-operating with a strap and buckle, substantially as set forth.

In testimony whereof I affix my signature in presence of two witnesses.

SIMON L. WALDMAN.
